UNITED STATES PATENT OFFICE.

ARTHUR P. PAINE, OF NEW HAVEN, CONNECTICUT, ASSIGNOR TO WINCHESTER REPEATING ARMS COMPANY, A CORPORATION OF CONNECTICUT.

SPOTLIGHT.

Application filed October 28, 1921. Serial No. 511,167.

To all whom it may concern:

Be it known that I, ARTHUR P. PAINE, a citizen of the United States, residing at New Haven, in the county of New Haven, State 5 of Connecticut, have invented certain new and useful Improvements in Spotlights; and I do hereby declare the following to be a full, clear, and exact description of the invention, such as will enable others skilled in 10 the art to which it appertains to make and use the same.

The present invention relates to battery hand lamps of the type in which the lamp bulb is movable with respect to the reflector 15 to change the spread of the beam of light delivered by the hand lamp. It is an object of the present invention to provide a cheap, reliable and well protected means for supporting and shifting the lamp. It is a 20 further object to provide reliable electrical connections whereby current from the battery can be delivered to the lamp bulb irrespective of its changes in position and whereby the lamp may be flashed or may be burned 25 continuously, as occasion requires.

In the accomplishment of the foregoing objects, and others hereinafter made clear, the lamp is mounted in a support which is rotatable in the casing of the hand lamp to 30 move the lamp axially of the casing. In the preferred embodiment, the support is threaded to the front metal head of the casing and means is provided for conveniently turning the support on its threads to advance or retract the lamp bulb.

In the accompanying drawings—

Fig. 1 is a sectional elevation of one embodiment of the present invention;

Fig. 2 is a fragmentary section of the 40 same embodiment;

Fig. 3 is a rear view of the reflector showing the three fingers by which the lamp support is rotated;

Figs. 4 and 5 are sections on the lines 4 45 and 5, respectively, of Fig. 1;

Fig. 6 is a detail of the lamp support;

Fig. 7 is a partial section of a modified form of lamp support.

In the embodiment illustrated in the 50 drawing, the hand lamp comprises a tubular casing 1 of insulating material which has a flaring metal head 2 secured permanently in position as by rivets 3. Threaded to this metal end is a cup-shaped lamp sup-

port 4 of insulating material having an integral recessed bottom. Mounted on this bottom is a flat plate 5 of metal having tangs 6 struck up therefrom and passed through openings in the bottom and there clinched over, as shown in the drawings. 60 Integral with plate 5 is a threaded lamp socket 7 in which the lamp 8 is mounted and by which electrical connection is established with the outer terminal of the lamp.

A metal cylinder 9 is mounted on the insulating bottom of the support to serve as a contact, this cylinder being held by the clinched tangs 6 of plate 5 and therefore being in permanent electrical connection with lamp socket 7. A battery 10 of dry cells 70 placed end to end in series connection within the casing has its upper terminal 11 in contact with a flat spring 12 which passes through the insulating bottom of the lamp support and has a free end housed in the recess of said bottom and bearing yieldingly against the inner terminal of the lamp. At the bottom of the battery is a coiled spring 13 which presses the battery forward against contact spring 12 and maintains continuous 75 connection with the latter irrespective of rotary and forward movement of the lamp support. Spring 13 is carried by a removable end cap 14 threaded to a collar 15 which is connected by a conductive strip 16 with 80 a switch housing 17. Secured to housing 17 by a rivet 18 is a yielding contact element 19 having a thumb piece or push button 20 adapted to make contact with the outwardly bent end 21 of the stationary conductive 85 strip 22 secured to the casing by rivet 23. The forward and inwardly bent end of strip 22 makes yielding connection with cylinder 9 while leaving that cylinder free to rotate and advance or retract with the lamp support. The thumb piece 20 of the switch mechanism can be used for flashing the lamp 90 as for signaling by the Morse code, and a thumb piece 24 mounted to slide on housing 17 has a bent finger 25 which by disengagement from a slot in element 19 can ride over the upper face of that element and hold thumb piece 20 in depressed and contact-making position.

A reflector 26 is mounted at the front end 105 of the casing and is spaced from and insulated from the threaded lamp socket 7. It has a central opening through which the

bulb of lamp 8 may pass. A lens 27 is spun into the rim of the reflector. This lens may be a plain lens, as shown or may have a curved face or faces. An adjustable collar 5 28 threaded to the front cylindrical end of the flaring metal head 2 detachably clamps the reflector against the end of the head. Secured to the bowl of the reflector as by soldering is a metal ring 29 (Fig. 3) carrying 10 three fingers 30, each of which passes loosely through a broad slot 31 in the insulatiⁿ lamp support. These fingers serve as means for rotating the lamp support in the threaded head when reflector 26 is rotated.

With the elements constructed and assembled as above described, the operator can change the spread of the beam of light from the hand lamp by first loosening collar 28 20 to unclamp reflector 26, and then turning the reflector on the front end of the metal head to cause its attached fingers 30 to rotate the lamp support 4 along the threads of metal head 2, thereby shifting the relative 25 position of lamp and reflector. During these adjustments, the contact cylinder 9 slides with a rotary movement along the inwardly bent end of conductor 22, but without interrupting the electrical connection and 30 spring 13 advances the battery with a sliding movement to maintain electrical connection between its terminal 11 and contact spring 12. Then collar 28 can be tightened up and the lamp is again secured against accidental 35 or inadvertment movement of the bulb with respect to the reflector.

Irrespective of the position of the lamp support, the switch mechanism at the side of the case, together with its associated parts, 40 is serviceable as means for making and breaking electrical connection between the cylindrical contact 9 and the coiled spring 13 at the other end of the battery. All of the parts above described are easily manufactured 45 and easily assembled and not easily destroyed or impaired by normal use, and all of the movable parts at the front end of the casing can be taken out for adjustment or repair, or to give access to the battery as 50 when the latter swells and becomes stuck in the tube and must be forcibly ejected preparatory to replacement by a new battery.

If desired the cup-shaped insulating lamp support 4, instead of being made entirely of 55 insulating material, may be made as shown in Fig. 7 with an insulating bottom 32 on which the contact cylinder 9' is mounted, and with a threaded metal shell 33 secured to the bottom by a flange and rivets 34. When 60 assembled, this metal collar 33 engages with the threads on the inside of the flaring metal head 2, of the hand lamp casing. A metal tube can be used in place of the insulating tube 1 without any changes other than that 65 of insulating the conductive strip 22 from

the metal tube as by a strip of insulation laid between the two and the use of insulated rivets.

Other changes in the details of the various elements and in their arrangement may be 70 made without departing from the spirit of the invention as defined by the appended claims.

I claim:—

1. In a hand lamp, the combination of a 75 casing, a battery therein, a lamp, a support for said lamp threaded to said casing, and means for turning said lamp support on its threads to move said lamp axially of said casing, thereby changing the spread of the 80 beam of light from said hand lamp.

2. In a hand lamp, the combination of a 85 casing, a battery therein, a lamp, a support for said lamp threaded to said casing, and means for turning said support to move said lamp axially of said casing and thereby change the spread of the beam of light from 90 said hand lamp.

3. In a battery hand lamp, the combination of a casing having a threaded metal 95 end, a lamp support threaded to said end, a lamp carried by said support, a battery in said casing, a lens and reflector carried by said casing, and means for turning said lamp support in said casing to move the 100 lamp with respect to the reflector and thereby change the spread of the beam of light delivered by said hand lamp.

4. In a hand lamp, the combination of a 105 casing, a battery therein, a lamp, a rotatable lamp support in said casing, a reflector for said lamp and means on said reflector for rotating said support to shift the position of said lamp in said reflector, substantially as described.

5. In a hand lamp, the combination of a 110 casing, a battery therein, a lamp, a threaded support for said lamp, a reflector for said lamp, and means on said reflector for turning said lamp support on its threads to move said lamp axially of said casing, thereby shifting the position of said lamp in said reflector and changing the spread of the beam of light from said hand lamp.

6. In a hand lamp, the combination of a 115 casing, a battery therein, a lamp, a support for said lamp threaded to said casing, a reflector for said lamp, and means actuated by said reflector for turning said support to move said lamp axially of said casing, and thereby shift the position of said lamp in said reflector, and change the spread of the beam of light from said hand lamp.

7. In a hand lamp, the combination of a 120 casing having a threaded metal end, a battery therein, a lamp support threaded to said metal end, a lamp carried by said support, a lens and reflector carried by said casing, and means on said reflector for turning said lamp support in said casing to move the 125 130 beam of light from said hand lamp.

- lamp with respect to the reflector and thereby change the spread of the beam of light delivered by said hand lamp.
8. In a hand lamp, the combination of a casing, a battery therein, a lamp connected with one terminal of said battery, a lamp support in said casing rotatable to move said lamp axially of the casing, a cylindrical contact connected with said lamp, and means for making and breaking electrical connection between said contact and the other terminal of said battery.
9. In a hand lamp, the combination of a casing, a battery therein, a lamp connected with one terminal of said battery, a threaded lamp support in said casing, means for turning said lamp support on its threads to move said lamp axially of said casing, thereby changing the spread of the beam of light from said hand lamp, a cylindrical contact connected with said lamp, and means for making and breaking electrical connection between said contact and the other terminal of said battery.
10. In a hand lamp, the combination of a casing, a battery therein, a lamp connected with one terminal of said battery, a support for said lamp threaded to said casing, means for turning said support to move said lamp axially of said casing, and thereby change the spread of the beam of light from said hand lamp, a cylindrical contact connected with said lamp, and means for making and breaking electrical connection between said contact and the other terminal of said battery.
11. In a hand lamp, the combination of a casing having a threaded metal end, a lamp support threaded to said end, a battery in said casing, a lamp carried by said support and connected with one terminal of said battery, a lens and reflector carried by said casing, means for turning said lamp support in said casing to move the lamp with respect to the reflector, and thereby change the spread of the beam of light delivered by said hand lamp, and means for making and breaking electrical connection between said lamp and the other terminal of said battery during said rotary movement.
12. In a hand lamp, the combination of a casing, a battery therein, a lamp connected with one terminal of said battery, a rotatable lamp support in said casing, a reflector for said lamp, means on said reflector for rotating said support to shift the position of said lamp in said reflector, and means for making and breaking electrical connection between said lamp and the other terminal of said battery.
13. In a hand lamp, the combination of a casing, a battery therein, a lamp connected with one terminal of said battery, a lamp support in said casing rotatable to move said lamp axially of the casing, a reflector for said lamp, means on said reflector for rotating said support to shift the position of said lamp in said reflector, and means for making and breaking electrical connection between said lamp and the other terminal of said battery.
14. In a battery hand lamp, the combination of a casing, having a threaded metal end, an insulating lamp support threaded to said end, a metal lamp socket mounted on said support, a lamp therein, a battery of dry cells in said casing, and having one end electrically connected with said lamp, a reflector for said lamp insulated from said socket and having a central opening through which the bulb of said lamp may pass, means adjustably clamping said reflector in position, means carried by said reflector and adapted to rotate said lamp support when said reflector is turned in said head, thereby changing the spread of the beam of light from said hand lamp, and means for making and breaking electrical connection between said lamp and the other end of said battery.
15. In a battery hand lamp, the combination of a casing, having a threaded metal end, a cup-shaped lamp support threaded to said end and having a bottom of insulating material, a threaded metal lamp socket mounted on said support, a lamp therein, a cylindrical contact on said support and connected with said socket, a battery of dry cells in said casing, and having one end connected with said lamp, a spring pressing against the other end of said battery, a reflector for said lamp insulated from said threaded socket and having a central opening through which the bulb of said lamp may pass, a lens for said reflector, means adjustably clamping said reflector against the end of said metal head, means carried by said reflector and adapted to rotate said lamp support when said reflector is turned in said head, thereby changing the spread of the beam of light from said hand lamp, and means for making and breaking electrical connection between said cylindrical contact and the spring at the other end of said battery.
16. In a battery hand lamp, the combination of a casing having a threaded metal end, a cup-shaped lamp support threaded to said end and having a recessed bottom of insulating material, a threaded metal lamp socket mounted on said support, a lamp therein, a cylindrical contact on said support and connected with said socket, a battery of dry cells in said casing, a contact spring in the recess of said insulating bottom and making electrical connection with one end of said battery, a coiled spring pressing against the other end of said bat-

- tery, a reflector for said lamp insulated from said threaded socket and having a central opening through which the bulb of said lamp may pass, a lens for said reflector, an adjustable collar clamping said reflector against the end of said metal head, means carried by said reflector and engaging said lamp support to rotate the same when said reflector is turned in said head, thereby 10 changing the spread of the beam of light from said hand lamp, and means for making and breaking electrical connection between said cylindrical contact and the coiled spring at the other end of said battery.
- 15 17. In a battery hand lamp, the combination of a casing having a threaded metal end, a cup-shaped lamp support threaded to said end and having a recessed bottom of insulating material, a threaded metal lamp socket mounted on said support, a lamp 20 therein, a cylindrical contact on said support and connected with said socket, a bat- tery of dry cells in said casing, a flat contact spring in the recess of said insulating bottom and passing therethrough to make 25 electrical connection with said battery, a coiled spring pressing against the other end of said battery, a reflector for said lamp insulated from said threaded socket and having a central opening through which the 30 bulb of said lamp may pass, a lens spun into the rim of said reflector, an adjustable collar clamping said reflector against the end of said metal head, fingers carried by said reflector and engaging said lamp support 35 to rotate the same when said reflector is turned in said head, thereby changing the spread of the beam of light from said hand lamp, and means for making and breaking electrical connection between said cylindrical contact and the coiled spring at the other 40 end of said battery.

In testimony whereof I affix my signature.
ARTHUR P. PAYNE.
